Primary Examiner—Robin V Webster(74) *Attorney, Agent, or Firm*—Pedersen & Co., PLLC; Ken J. Pedersen; Barbara S. Pedersen(57) **CLAIM**

The ornamental design for a filter block for liquid filtration, as shown and described.

DESCRIPTION

FIG. 1 is a top perspective view of the invented design for a filter block for liquid filtration.

FIG. 2 is a top view of the filter block of FIG. 1.

FIG. 3 is a bottom view of the filter block of FIG. 1.

FIG. 4 is a side view of the filter block of FIG. 1, with right and left side views being the same.

FIG. 5 is an end view of the filter block of FIG. 1, with right and left end views being the same.

FIG. 6 is a cross-sectional view of the filter block taken along 6—6 of FIG. 1; and,

FIG. 7 is a cross-sectional view of the filter block taken along 7—7 of FIG. 1.
